 W. N. Matthews Corporation, St. Louis, Mo.,
 a corporation of Missouri

Application October 15, 1942, Serial No. 462,179

6 Claims. (Cl. 200—126)

This invention relates to electric switches, and with regard to certain more specific features, to repeating electric fuse switches.

The invention is an improvement upon the type of construction shown in my United States Patent 2,240,253, dated April 29, 1941.

Among the several objects of the invention may be noted the provision of a foolproof repeating fuse switch having a simple, compact, reliable and enclosed structure for providing time-delay action between successive circuit reclosures; and the provision of a switch of the class described which, despite the time-delay features, effects snap-action circuit reclosure through successively operative fuse holders. Other objects will be in part obvious and in part pointed out herein-after.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a side elevation of the switch shown in closed position and ready for operation;

Fig. 2 is a right-side elevation of Fig. 1;

Fig. 3 is a fragmentary horizontal section taken on line 3—3 of Fig. 1, but reversed in position;

Fig. 4 is a vertical section taken on line 4—4 of Fig. 2;

Figs. 5 to 7 are views similar to Fig. 4, showing successive operating positions of the parts involved in Fig. 4; and,

Fig. 8 is a fragmentary view of a lower portion of Fig. 1 illustrating opening action of the lower end of the fuse holder, the same being viewed on line 8—8 of Fig. 2.

Similar reference characters indicate corresponding parts throughout the several views of the drawings.

Referring now more particularly to Fig. 1, there is shown at numeral 1 an arm for holding a vertical insulator 3. At the upper end of this insulator is held a laterally extending bracket 5, the same being held in place by a screw clamp 7. This bracket 5 has suitable openings 9 for receiving (in whichever opening desired) a line wire connector 11.

Pivoted to the bracket 5 at points 13 is a multiple-contact arm 15. This arm 15 is made up rigidly with struts 17 carrying at their ends contact hoods 19, 21 and 23. Each hood has skirts

2, and wings 4 serving as weather guards. Each also has a cam surface 17 leading into a socket 19.

The hoods 19, 21 and 23, along with the struts 5 17 pivot as a unit upon said bearings 13 and, in order to assure electrical transmission between the bracket 5 and the arm 15, braided copper wire 25 connects the two. This wire allows for free relative movement between the members 5 and 10 15.

A tension spring 27 reacts between an eye 29 carried on the arm 15 and an eye 31 carried on the bracket 5. The line C—L of axial tension of this spring 27 passes beneath the pivot 13, thereby tending to bias the arm 15 downward. The maximum downward position that may be assumed by the arm 15 is determined by lugs 33 on the arm 15 cooperating with adjustable stops 35 on the bracket 5.

20 On the lower end of the insulator 3 is a bracket 37 held in place by means of a saddle piece 38 and screws 39. This bracket also carries openings such as 9, one of which receives a line wire connector 11. The bracket 37 carries three 25 pairs of arms enumerated respectively as 41, 43 and 45, arranged in descending order by pairs as indicated in Figs. 1 and 2. Each pair has supporting slots 47 for gudgeons 49 of fuse holder assemblies indicated at A, B and C, respectively.

30 Each fuse holder assembly A, B and C is constituted by an insulating fuse tube 51 carrying an upper conducting head 53 into which is screwed a round-nose conducting cap 55. Each cap 55 may be removed from its head 53, for the purpose of inserting a fuse link 57 through the fuse tube 51 and thereafter screwing down the head 55 to hold the upper end of said link. The link passes through the fuse tube and out of its lower end. At the lower end of each fuse tube 51 is a 35 clamp 59 carrying an extension eye 61. Pivoted at 63 to the clamp 59 is an arm 65 of bell-crank shape carrying the respective pair of gudgeons 49 for the fuse holder assembly under consideration. This bell-crank arm 65 has a normal position such as shown in Fig. 1, the unbroken fuse link 57 holding it in such position. The fuse link maintains the stated position because of its attachment to the arm 65 at a screw terminal 67 and its attachment at 55.

40 In order to hold a fuse holder assembly upright at positions B or C in Figs. 1 and 2, each eye 61 is provided with a lateral finger 69. In the cases 45 where a fuse link assembly (all the assemblies are alike) is inserted in the brackets 43 or 45 (positions B or C), the fingers 69 serve support-

ing purposes in connection with hooks 71 pivoted at 73. Each hook 71 is biased downward by a spring 75. Hence when fuse holder assemblies are positioned with their gudgeons 49 in the slots 47 at positions B or C, the levers 65 at this time being held against the lower ends of the tubes 51 by the links 57, and rotated outward, the hooks 71 will catch the fingers 69 and support these two fuse holder assemblies in the B and C positions shown in Fig. 2.

Each arm 11 is prevented from descending too far after release by means of contact between a stop 10 on the arm and the upper surface of the respective adjacent support 43 or 45 as the case may be.

The fuse holder assembly that is placed in the A position (Fig. 2) also carries a finger 69 but only for the purpose of interchangeability and uniformity. When a fuse holder assembly is placed in position A the finger 69 is of no use otherwise, because when the fuse holder is rotated upward in position A its contact head 55 engages the sloping cam surface 71 of the socket 19 and cams the arms 15 upward. Then the contact portion 55 moves into the socket 19, whereupon the bias of the spring 27 in biasing the arm 15 downward acts to hold the fuse holder assembly in position A. The fuse holder assemblies in positions B and C are spaced at increasing distances from the sockets in members 21 and 23 by reason of their descending order of support.

In order to delay circuit reclosing actions through the fuse holders at positions B and C, a time-delay mechanism M is used. This mechanism comprises a gear box 81 rigidly fastened to the bracket 5 by means of a bolt 83.

The box is provided with a cover 85. Within is a main shaft 87 which also reaches exteriorly. Here the shaft 87 is provided with a keyed arm 89 having at its end an arcuate slot 91 for angularly adjustable connection at 93 with an arm 95. The end of the arm 95 is pivoted at 97 to an offset connecting link 99 which in turn is pivoted at 101 to one side of the contact arm 15. Thus downward rotation of the arm 15, through the linkage 99, 95, and 89, tends to rotate the shaft 87. The purpose of the rotary clamping adjustment at the slot 93 is to obtain angular phase adjustment between the arm 15 and the shaft 87.

Referring to the interior of the box 81, the shaft 87 has keyed to it a bifurcated arm 103 having a pivot pin 105 for a pair of pawls 107 and 109, both of which, by means of spring 113, are normally biased toward engagement with a ratchet wheel 111. The ratchet wheel 111 is on a common shaft 115 with a gear 117 that meshes with a pinion 119. Pinion 119 forms a rigid cluster (on a countershaft 120) with a gear 121 which meshes with a pinion 123 on a shaft 125, the latter also carrying an escapement wheel 127. The teeth 129 of the escapement wheel successively contact pallets 131 struck up from an oscillating escapement anchor wheel 133. Thus any torque on the ratchet 111 is transmitted through the gearing 117, 119, 121, 123 to the escapement constituted by the members 127, 131 and 133. This escapement provides a time-delay action. The successive oscillating actions of the wheel 133 in effecting escapement are indicated in Figs. 4 to 7.

The pawl 107 has a catch for the ratchet wheel 111 which is lower than (or ahead of) the catch of the pawl 109. Therefore, when the arm 15 is up, as indicated in Fig. 4 (the position which it assumes when resting upon the fuse holder assem-

bly A), the catch of pawl 107 is engaged with the ratchet while the catch of the pawl 109 is not, the latter being spaced some distance from the ratchet.

Upon blowing of the fuse in the fuse holder assembly at A and dropping out of this assembly, the bias of the arm 15 is brought to bear (through the mechanism 99, 95, 89, 87, 103) to pull down the pawl 107 which at this time is in engagement with the ratchet wheel 111. The result is that the escapement mechanism outlined is driven. The escapement mechanism provides time-delay while permitting movement until the next succeeding socket 19 of member 21 approaches the fuse link assembly positioned at B. However, before contact is made between 21 and the upper end of this fuse link assembly at B, the catch of the pawl 107 is arranged to slip from engagement with the ratchet 111 (Fig. 5) so as to bring about a sudden contact between the member 21 and the top of this second fuse link assembly. This tends to avoid arcing contact. At the same time the catch of the pawl 109 comes near to initial engagement with the ratchet 111, as indicated in Fig. 5.

Next, when the fuse link in the fuse holder assembly at B blows, and that fuse holder falls away, thus withdrawing its support from the arm 15, almost immediate engagement between the pawl 109 and the ratchet 111 couples up the gear train for time-delay action as indicated between Figs. 5 and 6. This is again under downward bias of arm 15. The time-delay action now proceeds until the socket 19 in member 23 approaches the head 55 of the third fuse holder assembly in position C. Before contact is made, the catch of pawl 109 slips from the ratchet 111 to permit final quick reclosing action of the circuit. The position of parts with the circuit closed through the fuse holder assembly at C is shown in Fig. 6.

Finally, when the fuse link in the fuse holder assembly at C blows, the corresponding fuse holder assembly drops out, and since neither pawl 107 nor 109 is engaging the ratchet wheel 111, the arm 15 moves down until the lugs 33 engage the stops 35. This ends its travel.

It is to be noted that when the upper pivoted contact arm 15 descends, it swings down into contact with the switcher in the B and C positions, the socket portions or cavities 79 in the members 21 and 23 tend to cam the fuse holders backward from the positions shown in Fig. 1, so that the respective pins 69 are drawn away from the associated notched portions of the hook 71. This is because the sockets or cavities 79 have a larger radius than the respective heads 55 which cooperate therewith, as indicated in Fig. 1. The socket in each hood 21 and 23 is positioned to strike its respective head 53 with the front slope of the cavity. In other words, the cavities in 21 and 23 are not positioned for initially centrally striking the heads 53. In the case of the first tube A under hood 19 such positioning is not necessary and in this case the cavity may be centralized over the head 53, since there is no catch for the pin 69 of tube A. Thus the front slope of each cavity in hoods 21 and 23 acts as a cam to drive the respective head 55 backward into the center or rear portion of the socket, whereby the latch releasing effect on the respective pins 69 on tubes B and C is obtained. The action, being like a blow, is very effective for the latch releasing purpose. The members 21 and 23 are stepped forward as indicated in Fig. 1 to permit proper coaction with the heads 53 of the forwardly

stepped tubes B and C. Thus, just prior to the falling out of the fuse holder from either the B or C position, the respective pin 69 is pushed back to be free of holding action by the respective hook 71. Hence the clearing position of the pin 69 shown in Fig. 8 is easily reached, without interference. This improves the reliability of the release.

Among the advantages of the invention is the fact that the time-delay mechanism is up above the arm 15 and out of the way, the same being compactly enclosed and arranged, controlling all of the fuse holder assemblies. The location of the time-delay apparatus leaves the region between the upper arm 15 and the lower arms 41, 43 and 45 entirely free for application and closing in manipulation of the fuse holders, just as is the case in a fuse holder in a non-repeating switch.

Another advantage is that in a very compact mechanism both a time-delay effect is obtained and also a quick action contact for a succeeding reclosure after a given time-delay.

The device is reliable, foolproof, and reclosure is simple, being simply rotary re-application of loaded fuse holders to arms 41, 43 and 45.

In addition, the operator may fuse and organize the device with any one or more of the fuse holders. For example, he may rely for time-delay action upon any pair of fuse holders, such as a pair at A and B or a pair at B and C. If greater time-delay is required for operating only a pair of fuse holders he may use the device with fuse holders at A and C only. Under the latter conditions the time-delay between release of fuse holder A and insertion of fuse holder C into the line is the sum of the ordinary time-delays between operations required between A and B plus B and C. This is because, when latch 107 releases and there is no fuse holder at B, the latch 109 hooks into the ratchet 111 and delays further motion of the arm 15 in its final travel into contact with the fuse holder at C (assuming the fuse holder at B to be missing).

Another feature is that the operation of the time-delay mechanism is not deleteriously affected by the position of the device as a whole. For example, although it is shown vertical in the drawings, various degrees of tilt will not affect it.

It will be understood that manipulation of the fuse holders is accomplished generally by use of the ball-end of a lineman's stick in the eyes 61, which are presented forwardly when the holders fall into depending positions. Fig. 8 shows an intermediate position in a falling operation, just before an eye 61 rotates to the said forward position.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A repeating switch comprising a support, spaced conducting means on the support, one of said conducting means constituting a series of pivot means, collapsible switch means respectively pivoted in descending order in said pivot means and collapsible in response to electrical overload

conditions applied thereto, the other conducting means being pivoted, means biasing said pivoted conducting means toward successive engagements with said switch means and normally contacting the highest of the same, time-delay means comprising a single escapement means, a single ratchet means driving said escapement, latches for the ratchet means, a linkage connecting said pivoted conductor and the latches, said latches being arranged to catch and release from the ratchet means successively.

2. A repeating fuse switch comprising a support, spaced conducting means on the support, one of said conducting means constituting a series of pivot means, substantially identical collapsible fuse switch means respectively pivoted in descending order in said pivot means and collapsible in response to overload current applied to the fuses, the other conducting means being pivoted, means biasing said pivoted conducting means toward successive engagement with said switch means and normally contacting the highest of the same, time-delay means comprising a single escapement means, a single train of gears driving the escapement means, a single ratchet means driving said train of gears, latches for the ratchet means, a linkage connecting said pivoted conductor and the latches, said latches being arranged to catch and release from the ratchet means successively.

3. A repeating switch comprising a support, spaced conducting means on the support, one of said conducting means constituting a series of pivot means, collapsible switch means respectively pivoted in descending order in said pivot means and collapsible in response to electrical overload conditions applied thereto, the other conducting means being pivoted, means biasing said pivoted conducting means toward successive engagements with said switch means when uncollapsed and normally contacting the highest of the same, time-delay means comprising a single escapement means, a single train of gears driving the escapement means, a single ratchet means driving said train of gears, latches driving the ratchet means, a linkage connecting said pivoted conductor and the latches, said latches being arranged to catch and release from the ratchet means successively, the catching period of a given latch being arranged for controlled biased movement of the pivoted conductor from the time that one switch member collapses and disconnects from the pivoted conductor until the pivoted conductor approaches the next non-collapsed fuse holder.

4. A repeating fuse switch comprising a support, spaced conducting means on the support, one of said conducting means constituting a series of pivot means, substantially identical collapsible fuse switch means respectively pivoted in descending order in said pivot means and collapsible in response to electrical overload applied to the fuses therein, the other conducting means being pivoted, means biasing said pivoted conducting means toward successive engagements with said fuse switch means and normally contacting the highest of the same, time-delay means comprising a single escapement means, a single train of gears driving the escapement means, a single ratchet means driving said train of gears, latches driving the ratchet means, a linkage connecting said pivoted conductor and the latches, said latches being arranged to catch and release from the ratchet means successively, the catching period of a given latch being arranged for control of the pivoted conductor from the time that one fuse switch member collapses from the pivoted conductor

until the pivoted conductor approaches but before it contacts the next non-collapsed fuse holder.

5. A repeating switch comprising a support, spaced conducting means on the support, one of said conducting means constituting a series of pivot means, a plurality of collapsible switch means respectively pivoted in descending order in said pivot means and individually collapsible in response to electrical overload conditions applied thereto, the other conducting means being pivoted, means biasing said pivoted conducting means toward successive engagements with said switch means and normally contacting the nearest of the same, time-delay means comprising a single escapement means, a single train of gears driving the escapement means, a single ratchet means driving said train of gears, latches driving the ratchet means, a linkage connecting said pivoted conductor and the latches, said latches being arranged to catch and release from the ratchet means successively, the catching period of a given latch being arranged for control of the pivoted conductor from the time that one switch member leaves the pivoted conductor by collapsing until the pivoted conductor approaches the next switch member, the latching however releasing from the ratchet means before contact is made with said second switch member, whereby said pivoted conductor may approach the second switch member untrammelled by the time-delay mechanism and under pure bias on said pivoted conducting means.

6. A repeating fuse switch comprising a sup-

port, spaced conducting means on the support, one of said conducting means constituting a series of pivot means, collapsible fuse holders respectively pivoted in descending order in said pivot means and collapsible in response to electrical overload conditions applied thereto, the other conducting means being pivoted, means biasing said pivoted conducting means toward successive engagements with said fuse holders and normally only contacting the nearest of the same, time-delay means comprising a single escapement means, a single train of gears driving the escapement means, a single ratchet means driving said train of gears, latches driving the ratchet means, a linkage connecting said pivoted conductor and the latches, said latches being arranged to catch and release from the ratchet means successively, the catching period of a given latch being arranged for control of the pivoted conductor from the time that one fuse holder leaves the pivoted conductor by collapsing until the pivoted conductor approaches the next non-collapsed fuse holder, said latch however releasing from the ratchet means before contact is made with said second fuse holder, whereby said pivoted conductor may approach the second fuse holder untrammelled by time-delay action and under pure bias on the pivoted conducting means, and means in said linkage for adjusting the angular phase relationship between said pivoted conductor and said latches.

THEODORE BIRKENMAIER.
